FOUNTAIN BRUSH

Glen S. Slough, Kansas City, Mo., assignor to Auto Craft Products, Inc., Kansas City, Mo., a corporation of Kansas

Application September 4, 1956, Serial No. 42,828

Term of patent 14 years

(Cl. D9—2)

Fig. 1.

Fig. 2.

Fig. 3.

Fig. 1 is a perspective view of a fountain brush, showing my new design;

Fig. 2 is a fragmentary side elevational view thereof; and

Fig. 3 is a fragmentary front elevational view thereof.

The handle is shown broken away in Figs. 2 and 3 for convenience of illustration only.

I claim:

The ornamental design for a fountain brush, as shown and described.
